CLAIM

The ornamental design for an electrical actuator for valves, as shown and described.

DESCRIPTION

FIG. 1.10 is a perspective view of an electrical actuator for valves, showing my new design;

FIG. 1.11 is another perspective view thereof;

FIG. 1.12 is another perspective view thereof;

FIG. 1.13 is another perspective view thereof;

FIG. 1.14 is a front view thereof;

FIG. 1.15 is a left side view thereof;

FIG. 1.16 is a right side view thereof;

FIG. 1.17 is a bottom view thereof; and

FIG. 1.18 is a top view thereof.
